US00D388051S

United States Patent [19]

Harada et al.

[11] Patent Number: Des. 388,051

[45] Date of Patent: **Dec. 23, 1997

[54] BATTERY

[75] Inventors: **Keiichi Harada, Osaka; Noriko Hameda, Hyogo; Chikara Kasai; Hitoshi Mikuriya, both of Kanagawa, all of Japan**

[73] Assignee: **Matsushita Electric Industrial Co., Ltd., Osaka, Japan**

[**] Term: **14 Years**

[21] Appl. No.: **52,608**

[22] Filed: **Apr. 1, 1996**

[30] Foreign Application Priority Data

Oct. 13, 1995 [JP] Japan 7-30620

[51] LOC (6) Cl. **13-02**

[52] U.S. Cl. **D13/103**

[58] Field of Search **D13/103; 429/96-100; 429/163, 176**

[57] CLAIM

The ornamental design for a battery, as shown and described.

DESCRIPTION

FIG. 1 is a perspective view of the front, top and left side of a first embodiment of a battery showing our new design; FIG. 2 is a front elevational view thereof;

FIG. 3 is a top plan view thereof;

FIG. 4 is a rear elevational view thereof;

FIG. 5 is a rear elevational view thereof;

FIG. 6 is a left side elevational view thereof;

FIG. 7 is a bottom plan view thereof;

FIG. 8 is a perspective view of the front, top and left side of a second embodiment of a battery showing our new design; FIG. 9 is a front elevational view thereof;

FIG. 10 is a top plan view thereof;

FIG. 11 is a rear elevational view thereof;

FIG. 12 is a rear elevational view thereof;

FIG. 13 is a left side elevational view thereof; and,

FIG. 14 is a bottom plan view thereof.
